[57] ABSTRACT

A door stop for a laterally movable door which is hung on a building wall includes a bracket mounted near the forward edge of the door on the surface toward the wall and a slide member which is horizontally slideable in the bracket and has an offset stop bar at its front end and ears at its rear end. As the door nears closed position the stop bar engages one door jamb, and the door continues to move until the bracket abuts the stop bar. The door is stopped in open position when the stop bar is engaged with the other door jamb and the bracket abuts the ears. A latch strike on the first jamb engages the stop bar to "snug" the door against the wall, and to permit the door to be locked shut.

DOOR STOP FOR A LATERALLY MOVABLE DOOR

BACKGROUND OF THE INVENTION

In any structure which has a sliding door mounted for lateral movement on a wall, some sort of a stop is necessary to stop the door in its closed position and also to stop the door in its open position. Such doors may be mounted either on the outside or on the inside of a building wall; but most commonly they are mounted on the outside of a wall as is common in pole frame buildings, barns, etc. A typical pole frame building provided with a sliding door and door stop is illustrated in Uphoff U.S. Pat. No. 3534431. The present invention is disclosed as applied to a structure of the type shown in the Uphoff patent.

A typical pole frame building has a frame using poles, with a treated wooden skirt nailed to the outside of the poles at ground level and extending upwardly for a distance which is at least 6 to 12 inches and may be 36 inches or so. Above skirt height there are girts nailed to the poles, and thin gauge corrugated metal siding is nailed to the girts with its lower edge overlapping the skirt by an inch or two. The typical sliding door has a wood framework and an outside skin of the corrugated sheet metal panels, and the lowest 3 to 4 inches of the bottom door frame member is not covered with corrugated metal so that it may provide a smooth surface for a bottom stay roller or door guide.

Heretofore the door stops commonly used for such doors have been mounted on the building structure, rather than on the door. As a rule the device which stops the door in closed position, and sometimes the device which stops the door in open position, embraces the edge of the door to restrain it from swinging in the wind and damaging the mounting trolleys, the door or the building. The door stop disclosed in the Uphoff patent is typical of those used with either single or double sliding doors, and it is apparent that a pair of generally similar stops could be mounted on the building skirt near the sidewalls to stop and restrain the doors in open position.

There are a number of disadvantages or limitations to the use of door stops which are mounted on the building. These include the following:

1. The stop usually must be mounted low, either on the building floor in the case of a closing stop for a pair of sliding doors or on the building skirt. When the door is moved vigorously to its open or closed position, it comes to an abrupt stop which causes it to cant or cock edgewise which exerts extreme stress on the door track and trolleys.

2. Modern pole type buildings have very attractive corrugated siding with a baked enamel surface, and a stop mounted on the outside of the building detracts from the appearance of the building.

3. In some cases a sliding door projects slightly beyond the building corner when the door is fully open, and in that case there is no structure on which to fasten a conventional stop for the open door and it is necessary to extend the skirt at the corner of the building with a short piece of plank to receive a stop. This is unsightly, and may be hazardous to persons walking past the building.

4. Even a single sliding door requires two stop devices, which involves extra cost and extra labor as com-

pared to a single device which could serve the same function.

A typical sliding door which slides outside the wall and the door jambs is of such dimensions that the closed door overlaps the jambs by about one-half inch to provide better protection against the wind and the elements than would be the case if the door were exactly the same width as the opening.

SUMMARY OF THE INVENTION

The present invention eliminates all of the above described disadvantages or limitations of the typical prior art door stops.

The device mounts near the forward edge of the door on the door surface which is toward the wall, so that when the door is closed no part of the stop structure is visible from the outside of the building.

Since the device mounts on the door, it may be in a vertical position which is near to or at the vertical center of gravity and thus eliminates undesirable cocking or canting of the door when it is moved forcibly to its closed or its open position.

Further, the inside mounting protects the stop elements from weather, and permits a person to install the device from inside the structure which can be most advantageous in bad weather.

The door stop structure allows the leading edge portion of the door to overlap the jamb in closed position, and also allows the door to be fully opened to permit utilization of the entire door opening.

When the door is in its fully closed position the cooperation between the stop slide member and the latch strike cams the door toward the building wall and holds it there.

The latch strike structure accommodates a locking pin to lock the sliding door from the inside for security reasons.

THE DRAWINGS

FIG. 1 is a fragmentary view of a wall, door opening and door of a pole building, seen from the inside with the door fully closed, and with the device of the present invention mounted on the door;

FIG. 2 is a fragmentary view on an enlarged scale which constitutes a front elevational view of the device of the invention with the associated parts of the door and door jamb;

FIG. 3 is a horizontal sectional view taken substantially as indicated along the line 3—3 of FIG. 2;

FIG. 4 is a sectional view taken substantially as indicated along the line 4—4 of FIG. 3;

FIG. 5 is a view similar to FIG. 2 with the door approaching its fully open position;

FIG. 6 is a horizontal sectional view taken substantially as indicated along the line 6—6 of FIG. 5; and

FIG. 7 is a view similar to FIG. 6 with the door in its fully open position.

DETAILED DESCRIPTION OF THE INVENTION

Referring to the drawings, and referring first to FIG. 1, a pole building has upright poles 10, a skirt 11 consisting of planks secured to the exterior of the poles, horizontal girts 12 which are also secured to the exterior of the poles, and siding consisting of corrugated metal plates 13. A doorway 14 is framed by a first jamb 15, a second jamb 16 and a lintel 17. A door, indicated generally at 18, includes a bottom frame member 19,

a top frame member 20, side frame members 21 and 22, cross frame members 23, upright frame members 24, and a corrugated metal skin 25 which matches the siding 13. A split tubular track 26 is mounted on the outside of the building on a track plank, and wheeled door suspension carriages 27 support the door in the track 26 for lateral sliding movement to close and expose the doorway 14. In modern pole buildings the metal siding 13 and door skin 25 is commonly of the type that has square corrugations extending vertically, and the outer surface of the metal has a baked enamel finish which makes the building quite attractive.

The device of the present invention constitutes the stop means, indicated generally at 30, which is preferably mounted on the center horizontal door frame member 23 so as to be substantially equidistant from the bottom door frame 19 and the carriages 27 to eliminate edgewise cocking or canting of the door if it is moved violently to its open or closed position. The stop means 30 includes a bracket, indicated generally at 31, a slide member, indicated generally at 32, and a strike, indicated generally at 33.

The bracket 31 is best seen in FIGS. 2 to 4 to include a top wall 34 and a bottom wall 35 connected by a plate 36 which spans the horizontal door frame member 23 so that the walls 34 and 35 serve as mounting flanges to receive screws 37 which are driven into the top and bottom of the frame member 23. The plate 36 has a recessed central area 36a which rests on the frame member 23 to establish the spacing of the plate from the frame member, and additional screws 37 impale the recessed area to aid in securing the bracket to the door. The plate 36 has a front end portion 38 and a rear end portion 39 which are inclined toward the frame member 23. Upper and lower margins 38a and 38b of the portion 38, and upper and lower margins 39a and 39b of the portion 39, are best seen in FIG. 5 to be spaced from the planes of the walls 34 and 35 and cooperate with the walls to form a horizontal slideway.

The slide member 32 is generally U-shaped, and consists of parallel upper and lower arms 40 and 41, respectively, connected by a bight portion, indicated generally at 42, which includes arm offsets 43 and 44 and an offset stop bar 45. The parallel arms 40 and 41 slide in the trackways defined by the bracket walls 34 and 35, the plate 36, the edges 38a-38b and 39a-39b, and the surface of the horizontal door frame member 23. The rear ends of the slide member arms 40 and 41 are bent upwardly and downwardly, respectively, to form ears 46 and 47. The offset arms 43 and 44 limit relative movement between the bracket 31 and the slide member 32 in one direction, while the ears 46 and 47 limit such movement in the opposite direction.

The latch strike 33 includes a mounting flange 48 having parallel slots 49 to receive mounting screws 50 by means of which the strike 33 is mounted with the flange 48 against the inner face 15a of the first jamb 15. Projecting outwardly from the bracket 48 is an integral strike body which includes a retaining portion 51 that is generally perpendicular to the surface 15a, a cam portion 52, and a return portion 53 that is generally parallel to the retaining portion 51. The retaining portion 51 and the return portion 53 are provided with aligned holes 51a and 53a, respectively, which receive the shank of a locking device such as the pin 54.

When the door is closed the stop bar 45 of the slide member 32 abuts the latch strike flange 48 and the for-

ward edge of the bracket 31, and the bracket is far enough from the front edge 21a of the door that in this position the front upright door frame member 21 overlaps the first jamb 15. Removal of the locking pin 54 from the aligned holes 51a and 53a permits the door to be moved toward its open position, and as seen in FIGS. 5 to 7 if the normal space between the door cross frame members 23 and the door jamb 16 is less than the depth of the bracket 31 (which is commonly the case since the slide member 32 is preferably fabricated from about $\frac{1}{2}$ inch rod) the inclined rear end portion 39 of the bracket plate 36 rides over the edge of the second jamb 16 and along the face of the jamb. If the door is close enough to the jamb 15 for the ears 46 and 47 to bear firmly against the inner face 16a of the jamb 16, engagement of the ears with the jamb stops further movement of the slide member 32 while the door continues to move toward its open position until the bracket 31 strikes the ears 46 and 47, and the door can continue to move until the offset arms 43 and 44 strike the inner surface 16a of the jamb 16 as seen in FIG. 7 and stop the door in its fully open position with the forward edge 21a of the door generally aligned with the inner face 16a of the jamb 16. On the other hand, if the door is hung far enough out from the building that the ears 46 and 47 either clear the jamb or ride lightly over its upright edge, then the slide member 32 and the bracket 31 retain their relative positions as illustrated in FIGS. 2 and 3 until the offset arms 43 and 44 engage the jamb 16 to stop further movement of the slide member 32 while permitting the door to continue its movement toward open position until the ears 46 and 47 abut the bracket.

When the door is moved toward closed position, the slide member 32 occupies the position illustrated in FIG. 6, and thus the offset stop bar 45 engages the inclined cam face 52 of the latch strike 33 which stops forward movement of the slide member 32 while permitting the door to continue its movement toward closed position until the front edge of the bracket 31 abuts the offset arms 43 and 44 and forces the stop bar 45 along the cam face 52 to force the door inwardly toward the building wall until the stop bar 45 rides onto the retaining surface 51 of the latch strike, and ultimately the stop bar 45 abuts the latch strike mounting flange 48 to stop the door in the fully closed position of FIG. 3.

The foregoing detailed description is given for clearness of understanding only and no unnecessary limitations should be understood therefrom, as modifications will be obvious to those skilled in the art.

I claim:

1. A door stop for a laterally movable door which has a forward edge and a rearward edge and which is hung on a building wall to selectively cover a door opening that has a first jamb and a second jamb, said door stop comprising, in combination:

55 a bracket providing a horizontal slideway mounted adjacent the forward edge of the door on the door surface which is toward the wall;

60 a slide member in said slideway and projecting from both ends of the bracket, said slide member having a front end and a rear end;

65 an integral offset stop bar at the front end of the slide member which engages the first jamb as the door nears fully closed position, and which is thereafter abutted by the bracket to stop forward movement

of the door, said stop bar engaging the second jamb when the door is in fully open position; and ears at the rear end of the slide member which are abutted by the bracket when the door is fully open.

2. The combination of claim 1 which includes a latch strike on the first jamb which has a camming surface that is engaged by the stop bar to force the forward edge portion of the door toward the wall, and a retaining surface.

3. The combination of claim 2 in which the latch strike has an opening which is to the rear of the stop bar when the door is fully closed, to receive a lock member.

4. The combination of claim 1 which includes a latch strike that has a mounting flange secured to the first jamb and an arm with an opening which is to the rear of the stop bar when the door is fully closed, to receive a lock member.

5. The combination of claim 4 in which the arm has a camming surface adjacent its free end that is engaged by the stop bar to force the forward edge portion of the door toward the wall.

6. The combination of claim 1 in which the bracket is mounted a short distance from the forward edge of the door so that when the stop bar is engaged with the jamb and abutted by the bracket the forward edge portion of the door overlaps the first jamb.

7. The combination of claim 6 which includes a latch strike on the first jamb which has a camming surface that is engaged by the stop bar to force the forward edge portion of the door toward the jamb and a retaining surface.

8. The combination of claim 1 in which the length of the slide member is substantially equal to the distance from the forward edge of the door to the rear of the bracket, so in open position the forward edge of the door is substantially aligned with the inner edge of the second jamb.

9. The combination of claim 1 in which the bracket has mounting flanges secured to the door and a plate between the flanges, the slide member is between the plate and the door, and the rear of the plate has a short, inclined end portion which may engage the second jamb to cam the door away from the wall.

10. The combination of claim 1 in which the bracket has parallel upper and lower walls which cooperate to form the slideway, and the slide member is essentially U-shaped with parallel arms that slide along said upper and lower walls, a bight portion which is offset to provide the stop bar, and outturned extremities on the arms which provide the ears.

11. The combination of claim 10 in which the bracket includes a plate that connects the upper and lower walls and is spaced from the door, the slide member is between the plate and the door, the end portions of the plate are inclined toward the door and have their upper and lower margins spaced inwardly from said walls, and the arms of the slide member are between said walls and said upper and lower margins.

12. The combination of claim 11 in which the bracket plate has a central recess providing a face which abuts the door surface to establish the distance between the plate surface and the door surface.
